UNITED STATES PATENT OFFICE.

RANSOM W. DAVENPORT, OF DETROIT, MICHIGAN, ASSIGNOR TO CHICAGO PNEUMATIC TOOL COMPANY, OF NEW YORK, N. Y., A CORPORATION OF NEW JERSEY.

HEAT ENGINE.

Original application filed April 25, 1924, Serial No. 708,936. Divided and this application filed July 24, 1925. Serial No. 45,905.

This invention relates to improvements in heat engines and is a division of my co-pending application Serial No. 708,936, filed April 25, 1924. The present invention is particularly adapted to employ in certain thermodynamic operations the novel working substance described and claimed in my copending application Serial No. 603,998 filed November 29, 1922; and for performing upon said novel working fluid such heat transforming operations as are described and claimed in my application Serial No. 570,015, filed June 21, 1922, for which a substitute application now copending, namely Serial No. 15,172, was filed March 12, 1925. The present and the aforesaid inventions constitute a closely related series.

Beside the above mentioned objects, the present invention provides means for utilizing the peculiar advantages inherent in the aforesaid inventions and applying them to the practical cooling of refrigerators. Other objects of my invention will appear hereinafter.

All refrigerating apparatus of the compression type hitherto known or used falls into one of two perfectly distinct and separate classes, i. e., the vapor-compression class or compressor-condenser-expander type, and the cold air type or compressor-cooler-expansion motor class. This separation is but the natural result of the essential and basic differences between the liquid-vapor refrigerants used in the former, and the ideal gas refrigerants used in the latter class of apparatus. It is emphasized that in the vapor-compression type of heat engine the refrigerating effect is obtained, not by expansion, but by vaporization of liquid at constant temperature and pressure, which liquid is fed as required and without expansion, i. e. without an increase in its volume, through a throttle valve loosely called the "expansion valve," into a so-called expansion coil where the liquid does not expand but evaporates at constant volume and pressure, whereas in the cold-air machine the entire refrigerating effect is obtained by expanding air or other gas (not vapor) with an increase in its volume, but obviously without evaporation in an expansion motor.

My improved heat engine differs from both the described types of heat engines in that I employ both an expansion device

and a boiler or vaporizing element in novel combination with a compressor and a condenser, in that I employ as a working substance a liquid and a gas substantially inert to and insoluble in the liquid, and in other respects hereinafter set forth as depicted in the accompanying drawings, in which:

Fig. 1 is a front elevational view of one form of my apparatus showing the refrigerator in section.

Fig. 2 is a side elevational view of those parts of the apparatus within the refrigerator proper, the refrigerator being shown in section.

In the embodiment of the invention chosen for the purpose of illustration the electric motor 18 is arranged to drive compressor 19 and expansion engine 20, and condenser 21 is connected to the outlet of the compressor and the intake of the engine through the separator 22, as shown. The evaporator tank 28 is supplied with the liquid component of the refrigerant through trap 24 and coil 25, from separator 22 by pipe 26, and the vapor-gas component is supplied to it from the discharge port of the engine 20 by the pipe 27. The top header 29 of the evaporator is connected to the intake of the compressor by pipe 30, thus completing the circuit. The tubes 23 (Fig. 2) connect the upper and lower headers of the evaporator, the whole forming the well-known Emulsieur-evaporator which I find well adapted to my purposes.

A suitable working substance having been charged into the machine with a supply of the liquid component in vessels 24 and 28 as shown, when motor 18 is started, the vapor-gas is compressed in 19, cooled in 21, the condensate is separated in 22, and the vapor-gas passes into the expansion engine and helps drive the compressor while expanding down to a lower pressure. For this expansion some heat is taken from the vapor-gas itself and some from the cylinder of the engine 20. This cylinder being in thermal contact with the coil 25 and the whole insulated, as shown, both the vapor-gas discharged through pipe 27 into 28 and the liquid fed to 28 through pipe 26 and trap 24 are cooled below the condenser temperature before entering the refrigerator, and the heat energy represented in this cooling, as well as the availability of the higher pres-

sure of the vapor-gas are here turned to useful account outside the refrigerator. The vapor-gas in pipe 27, still under pressure expands into chamber 28 causing the liquid 5 therein to bubble up through the tubes 23, and the liberated vapor and vapor-air passes back to the intake of the compressor through pipe 30.

It is to be understood that my expander, 10 instead of producing the entire refrigeration as would be the case in the old type of expansion machines, is employed in my novel combination with the object of pre-cooling the refrigerant from the relatively 15 high temperature at which it leaves the condenser toward the lower temperature maintained in the refrigerator by the evaporation of liquid in the boiler 28-23-29, and of transforming the heat represented by this 20 temperature difference into kinetic energy.

While but one form of the invention has been herein shown and described it is to be understood that the invention is not limited to the specific details thereof but covers all 25 changes, adaptations, and modifications within the scope of the appended claims.

I claim:

1. A heat engine adapted to the circulation 30 of a working substance having liquid and gaseous components comprising a compressor, a condenser, an expansion device in dynamic relation with said compressor, a boiler for containing the liquid component of the refrigerant, and pipes interconnecting said elements arranged to conduct the gaseous component of the refrigerant from said condenser to said expansion device and thence to said boiler beneath the level of the liquid refrigerant therein.

40 2. A heat engine adapted to the circulation of a working substance having liquid and gaseous components comprising a compressor, a condenser, an expansion device in dynamic relation with said compressor, a 45 boiler, a trap into which said condenser discharges, means conducting the liquid component of the refrigerant from said trap to said boiler, and means conducting the gaseous component of the refrigerant from said 50 trap to said expansion device and thence to the lower portion of said boiler.

3. A heat engine adapted to the circulation 55 of a working substance having expandable and non-expandable components comprising a compressor, a condenser and a boiler, and means for expanding said expandable component from ordinary condenser pressure so as to extract heat from said non-expandable component.

60 4. A heat engine adapted to the circulation 65 of a working substance having expandable and non-expandable components comprising a compressor, a condenser and a boiler, and means for expanding said expandable component in successive stages in ther-

mal and in actual contact with said non-expandable component so as to extract heat from the latter.

5. A heat engine adapted to the circulation 70 of a working substance having expandable and non-expandable components comprising a compressor, a condenser and a boiler, and means conducting said components separately from said condenser to said boiler, and means for expanding said expandable component in thermal contact with 75 said non-expandable component so as to extract heat from the latter.

6. A heat engine adapted to the circulation 80 of a working substance having liquid and gaseous components comprising a compressor, a condenser, an expander, and a boiler, and means conducting the liquid and gaseous components from said condenser 85 separately to said boiler, the gaseous component being directed through said expander.

7. A heat engine adapted to the circulation 90 of a working substance having liquid and gaseous components comprising a compressor, a condenser and a boiler, means conducting the liquid and gaseous components from said condenser separately to said boiler, and means for partially expanding 95 said gaseous component prior to its admission to said boiler.

8. A heat engine adapted to the circulation 100 of a working substance having liquid and gaseous components comprising a compressor, a condenser and a boiler, said boiler being arranged to contain a body of said liquid, and means for conducting the liquid and gaseous components of the circulated working substance from said condenser 105 separately to said boiler, the gaseous component being expanded into the lower part of said boiler so as to enter the same beneath the level of the body of liquid therein.

9. A heat engine adapted to the circulation 110 of a working substance having liquid and gaseous components comprising a compressor, a condenser and a boiler, said boiler being arranged to contain a body of said liquid, means for conducting the liquid and gaseous components of the circulated working substance from said condenser 115 separately to said boiler, the gaseous component being admitted to said boiler, adjacent the bottom thereof so as to enter beneath the level of the body of liquid therein, and means for partially expanding said gaseous component prior to its admission to said boiler.

10. A heat engine adapted to the circulation 125 of a working substance having liquid and gaseous components comprising a compressor, a condenser and a boiler, said boiler being arranged to contain a body of said liquid, means for conducting the liquid and gaseous components of the circulated work- 130

- ing substance from said condenser separately to said boiler, the gaseous component being admitted to said boiler adjacent the bottom thereof so as to enter beneath the level 5 of the body of liquid therein, and an expansion engine in dynamic relation with said compressor for utilizing a portion of the pressure of said gaseous component prior to its admission to said boiler.
- 10 11. Refrigerating apparatus utilizing as a refrigerant a physical mixture of a liquid and a gas comprising a compressor, a condenser, and an evaporator for containing a body of said liquid, said compressor being arranged to withdraw mingled gas and vapor of said liquid from said evaporator and discharge the same into said condenser, means for conducting the condensed and the non-condensable products of said condenser 15 separately to said evaporator and means acted on by said non-condensable product for extracting heat from said condensed product.
12. Refrigerating apparatus utilizing as a refrigerant a physical mixture of a liquid and a gas comprising a compressor, a condenser, and an evaporator for containing a body of said liquid, said compressor being arranged to withdraw mingled gas and vapor 20 of said liquid from said evaporator and discharge the same into said condenser, means for conducting the liquid and gaseous products of said condenser separately to said evaporator, and means for pre-cooling said 25 gaseous product by expansion prior to its admission to said evaporator.
- 30 13. Refrigerating apparatus utilizing as a refrigerant a physical mixture of a liquid and a gas comprising a compressor, a condenser, and an evaporator for containing a body of said liquid, said compressor being arranged to withdraw mingled gas and vapor of said liquid from said evaporator and discharge the same into said condenser, means for conducting the condensed and the non-condensable products of said condenser 35 separately to said evaporator, and means utilizing expansion of said non-condensable product for precooling both said products prior to their admission to said evaporator.
- 40 14. Refrigerating apparatus utilizing as a refrigerant a physical mixture of a liquid and a gas comprising a compressor, a condenser, and an evaporator for containing a body of said liquid, said compressor being arranged to withdraw mingled gas and vapor of said liquid from said evaporator and discharge the same into said condenser, means for conducting the liquid and gaseous 45 products of said condenser separately to said evaporator, means for extracting heat from said liquid product by expansion of said gaseous product, and means for controlling the level of said liquid in said evaporator.
- 50 15. Refrigerating apparatus utilizing as a refrigerant a physical mixture of a liquid and a gas substantially insoluble in the liquid comprising an evaporator for containing a body of said liquid, a compressor connected to the upper portion of said evaporator, 55 a condenser into which said compressor discharges, means conducting the liquid product of said condenser to said evaporator, means for conducting the gaseous product of said condenser in a separate path into said evaporator beneath the level of said body, and an expansion device acted upon by said gaseous product to precool the same prior to its admission to said evaporator.
- 60 16. Refrigerating apparatus utilizing as a refrigerant a physical mixture of a liquid and a gas substantially insoluble in the liquid comprising an evaporator for containing a body of said liquid, a compressor connected to the upper portion of said evaporator, a condenser into which said compressor discharges, a trap separating the discharge of said condenser into its liquid and gaseous components, means for conducting the liquid from said trap to said evaporator, an expansion device, and means for passing said gaseous component through said device and thence into said evaporator adjacent the bottom thereof.
- 65 17. Refrigerating apparatus utilizing as a refrigerant a physical mixture of a liquid and a gas substantially insoluble in the liquid comprising an evaporator for containing a body of said liquid, a compressor connected to the upper portion of said evaporator, a condenser into which said compressor discharges, a trap separating the discharge of said condenser into its liquid and gaseous components, a pipe conducting the liquid from said trap to said evaporator, an expansion engine, and means passing said gaseous component through said expansion engine and thence into said evaporator adjacent the bottom thereof, said pipe being disposed in thermal contact with said engine thereby to precool the liquid delivered to said evaporator.
- 70 18. Refrigerating apparatus utilizing as a refrigerant a physical mixture of a liquid and a gas substantially insoluble in the liquid comprising a refrigerator, an evaporator therein for containing a body of said liquid, a compressor connected to the upper portion of said evaporator, a condenser into which said compressor discharges, a trap separating the discharge of said condenser into its liquid and gaseous components, a pipe conducting the liquid from said trap to said evaporator, an expansion engine in dynamic 75 relation with said compressor and having its cylinder disposed in an insulated compartment, means passing said gaseous component from said trap through said engine to precool the same and thence conducting the same into said evaporator adjacent the bot-

tom thereof, said pipe being coiled about the cylinder of said engine to precool the liquid passing therethrough.

19. A heat engine adapted to the circulation of a working substance having liquid and gaseous components comprising a compressor, a condenser and a boiler, and means conducting the liquid and gaseous components from said condenser separately to said

10 boiler.

20. A heat engine adapted to the circulation of a working substance having liquid and gaseous components comprising a compressor, a condenser and a boiler, and means

15 for effecting the substantially continuous feeding of the liquid and gaseous compo-

nents from said condenser separately to said boiler.

21. A heat engine adapted to the circulation of a working substance having liquid and gaseous components comprising a compressor, a condenser, an expander, and a boiler, and means conducting the liquid and gaseous components from said condenser separately to said boiler, said gaseous component passing to said boiler through said

20
